UNITED STATES PATENT OFFICE.

PETER A. MURAF, OF DAYTON, OHIO.

IMPALING ARTICLE.

1,242,965.

Specification of Letters Patent. Patented Oct. 16, 1917.

Application filed November 18, 1914. Serial No. 872,792.

To all whom it may concern:

Be it known that I, PETER A. MURAF, a subject of the Czar of Russia, residing at Dayton, in the county of Montgomery and State of Ohio, have invented certain new and useful Improvements in Impaling Articles, of which the following is a specification.

My invention relates to forks and particularly to table forks.

The main objects of my invention are to provide an improved means coöperating with a fork operable to dislodge impaled food; to provide a construction of fork provided with a food-dislodging element or device capable of being fastened to the fork against movement; to provide a construction of slidable dislodging means provided with food-tine engaging portions and fork-arm engaging portions, and to provide a special construction of slidable dislodging means made of bendable material to enable its attachment to the fork.

With a view to attaining the foregoing objects as well as additional objects, as will become apparent from the description herein-after following taken in connection with accompanying drawings illustrating the preferred embodiment, the invention resides in certain novel features of construction, combination and arrangement of parts.

In said drawings:—

Figure 1 is a perspective view of a fork having my improved attachment fastened thereto, and

Fig. 2 is a side elevation of the parts of Fig. 1.

Referring specifically to the drawings, the fork is generally designated A and is preferably of a specific construction so as to coöperate with the specific construction of the food-dislodging member or element which is generally designated B.

Fork A is bent from a single strand of flexible wire so as to provide a handle having parallel side arms 1 and a connecting portion 2 which curves upwardly and laterally from the arms 1 and which curves in the path of an arc described from an axis line parallel with and intermediate the arms 1. The specific shape of the connecting por-

tion 2 enables it to coöperate with the dislodging element as will be later set forth. Extending inwardly from the arms 1 are stop portions 3 and extending downwardly from the portions 3 midway of their outer ends are portions 4 which are coiled and twisted together for the purpose of rigidifying the structure. Tines 5 extend from the portions 4 having diverging arms 6 adjacent the portions 4 from which diverging arms depend the straight portions of the tines which are parallel with and in line with the arms 1. Reinforcing lobes 7 are provided by bending or deflecting the tines outwardly at or adjacent the junction of the diverging arms 6 and the straight portions of the tines.

A strand of flexible or bendable wire is also preferably used in the manufacture or construction of the dislodging member or element B as is shown in the drawings. Dislodging element B has a laterally extending loop 8 to be arranged on the opposite side of the arms 1 to the connecting portion 2. Guide arms 9 depend from the loop 8 and adjacent the loop are provided with laterally offset coils 10 which form eyelets through which the arms 1 of the handle of the fork pass and slide. Arms 9 at their lower extremity extend inwardly at 11 and from the inwardly extending portions 11 depend portions 12 which are coiled and twisted together and from which extend laterally in opposite directions fastening arms 13 which are provided with eyelets 14 at their outer ends through which the tines 5 pass.

In the manufacture of the article, the fork A and dislodging elements B are made separately and then fastened together. In fastening the sections together, fork A is held at an angle to the dislodging element B so that the portion 2 will pass through the eyelets 10 whereupon the fork and dislodging element may assume a vertical position. The specific curving of the arm 2 facilitates its passage through the eyelets 10 for the purpose of properly mounting the arms 1 in the eyelets. After the fork and dislodging element have been connected as described, and the portions held in a vertical position, the dislodging element will slide downwardly until the coils 10 strike the arms 3.

At this stage the arms 13 will be directly opposite the piercing points of the tines 5. Said arms 13 being flexible, they are then bent downwardly slightly and the tines 5 passed therethrough. After passage of the tines through the eyelets 14, the arms 13 will return to their normal horizontal position but with the tines located in the eyelets 14 thereof.

- 10 My improved fork device is complete when the parts are connected as just described. Prior to use, the dislodging element B is drawn upwardly, sliding on the tines 5 and arms 1 by the provision of the eyelets 10 and 14, to its uppermost position. In moving to this position, the inner walls of the eyelets 14 engage the lobes 7 which cause the tines 5 to yield or spring inwardly toward each other and the eyelets 14 to pass 20 the same. When the eyelets 14 are above the lobes, it will be realized that the dislodging element is mounted against accidental displacement in a downward direction. In use the portion 2 is held in the 25 palm of the hand between the index finger and the thumb, and the thumb extends across the portion 8. While thus held, the fork may be thrust into an article, for instance food, and when the article is to be dislodged 30 from the tines, the thumb may be pressed downwardly against the portion 8 which depresses the dislodging element causing it to slide downwardly past the lobes 7 so that the arms 13 will engage the impaled 35 article and remove it from the tines 5.

It will be realized that my improved fork overcomes the necessity of bringing the fingers into engagement with an impaled article in order to dislodge it so that the article 40 may be handled in a more sanitary manner and also so that the article may be handled more expeditiously.

While my improved fork is particularly designed for table use, nevertheless the improvements may be embodied in forks generally, for instance in pitch forks, without departing from the spirit and scope of my invention.

It is to be understood that inasmuch as 50 I have shown only the preferred embodiment of my invention, that changes in the details of construction, arrangement and combination of the parts may be resorted to without departing from the spirit and 55 scope of the invention.

Having thus described my invention what I claim is:—

1. In combination with an impaling article member, a dislodging member, one of 60 said members having a frame with side arms, the other member having side arms, two of said side arms being coiled intermediate their ends to provide eyelets into which the remaining side arms are insertible through 65 movement of one member relatively to the

other member initiated when the members are at an angle to each other.

2. In combination with an impaling article member, a dislodging member, one of 70 said members having side arms, the other member having side arms, the side arms of one member being coiled intermediate their ends to provide eyelets and the side arms of the other of said members extending laterally and inwardly at a portion 75 thereof to facilitate insertion into the eyelets through movement of one member relatively to the other member initiated when the members are at an angle to each other.

3. In combination with an impaling article member, a dislodging member mounted thereon and slideable relatively thereto, and means to positively secure the members against accidental relative sliding movement 80 when the dislodging member is at the limit of its retracting movement and yet permit said members to be moved forcibly, said means including elements one of which is located on each member, one of said elements being movable relatively to the other element 85 and operable by the movement of the members relatively to each other.

4. In combination with an impaling article, a dislodging element slidably mounted 95 thereon, means to fasten said article and element against relative sliding movement, said article having a handle extending at an angle to the remainder thereof, and said dislodging element having a handle extending 100 at an angle to the remainder thereof, said handles extending in different directions for the purpose specified.

5. In combination with an impaling article having side arms and a connecting arm, inwardly extending arms at the base of said side arms, and tines in continuation of said inwardly extending arms, one of said tines being provided with a lobe, a dislodging element having a handle and side arms depending therefrom, said side arms of the 105 dislodging element being provided with eyelets through which the side arms of the handle pass, and fastening arms in continuation of said side arms of the dislodging elements, said tines engaging said fastening 110 arms one of said fastening arms being engageable with said lobe.

6. In combination with an impaling article having a handle provided with side arms and with a laterally extending connecting arm, inwardly extending arms adjacent one extremity of the side arms, arms in continuation of said inwardly extending arms depending therefrom and being fastened together, and tines depending from 115 said depending arms, one of said tines being provided with a lobe and being yieldable, a dislodging element having a laterally extending handle, side arms depending from 120 said handle provided with eyelets through 125 said handle provided with eyelets through 130

which the side arms of the article handle pass, arms in continuation of the side arms of the dislodging elements fastened together, and fastening arms extending laterally from said latter arms and being provided with eyelets through which said tines pass, said laterally extending arms being yieldable for the purpose of facil-

tating their connection with and detachment from the tines. 10

In testimony whereof I affix my signature in presence of two witnesses.

PETER A. MURAF.
